UNITED STATES PATENT OFFICE.

JOHN H. BREWER, OF LOUISVILLE, KENTUCKY.

TENT.

1,253,776.

Specification of Letters Patent. Patented Jan. 15, 1918.

Application filed November 11, 1916. Serial No. 130,862.

To all whom it may concern:

Be it known that I, JOHN H. BREWER, a citizen of the United States, residing at Louisville, in the county of Jefferson and State of Kentucky, have invented certain new and useful Improvements in Tents, of which the following is a specification, reference being had to the accompanying drawings.

10 This invention relates to certain improvements in tents and has relation more particularly to the supporting structure therefor; and it is an object of the invention to provide a device of this general character having novel and improved means whereby the several parts thereof may be assembled or disassembled with convenience and facility.

It is also an object of the invention to provide a device of this general character 20 including a novel and improved frame consisting of separable sections together with tensioning means common to all of said sections for holding the same in assembled relation.

25 A still further object of the invention is to provide a device of this general character having novel and improved means whereby the same may be readily transported and whereby the same when disassembled may be packed within a minimum of space.

The invention consists in the details of construction and in the combination and arrangement of the several parts of my improved tent whereby certain important advantages are attained and the device is rendered simpler, less expensive and otherwise more convenient and advantageous for use, all as will be hereinafter more fully set 35 forth.

40 The novel features of the invention will hereinafter be definitely claimed.

In order that my invention may be the better understood, I will now proceed to describe the same with reference to the accompanying drawings, wherein—

45 Figure 1 is a view in perspective illustrating the supporting structure of my improved tent, the covering or walls being omitted;

50 Fig. 2 is a transverse vertical sectional view taken through a complete tent constructed in accordance with an embodiment of my invention;

55 Fig. 3 is a fragmentary view partly in elevation and partly in section illustrating the tensioning member as herein set forth;

Fig. 4 is a fragmentary view partly in section and partly in elevation illustrating in detail a connection at a corner of my improved frame as herein disclosed; 60

Fig. 5 is a fragmentary view in elevation of an end portion of one of the bars as herein embodied and disclosing a slightly modified form of construction; 65

Fig. 6 is a fragmentary view in perspective of the coacting end portions of the sections comprised in certain of the bars as herein set forth;

Fig. 7 is a view partly in elevation and 70 partly in section illustrating an embodiment of my invention wherein my improved tent is disclosed as being used as a garage and illustrating means whereby the vehicle may be locked within the tent; 75

Fig. 8 is an enlarged fragmentary view in perspective of an end portion of the locking member as disclosed in Fig. 7;

Fig. 9 is a view in top plan of the frame 80 or supporting structure of a tent constructed in accordance with a further embodiment of my invention; and

Fig. 10 is a vertical sectional view taken through the device as disclosed in Fig. 9.

As disclosed in Figs. 1 to 8 inclusive, 85 A—A denote the bottom longitudinal bars of my improved tent structure and which are adapted to rest upon the ground or other supporting surface, and as herein disclosed, each of said bars comprises two sections 1, 90 the adjacent ends of which being reduced as indicated at 2, in Fig. 6 and with which coact the sleeve 3 for maintaining said sections 1 in assembled relation and also permitting said bars A to occupy a minimum 95 of space during transportation or when the tent is in storage.

B—B denote the upper longitudinal bars of my improved structure and which are in vertical alignment with the bars A and 100 maintained in predetermined spaced relation thereto through the medium of the corner uprights or bars C and the intermediate vertical bars or uprights D. The bars B are also sectional as has been particularly 105 set forth relative to the bars A and the sections of said bars B are maintained in assembled relation through the medium of the removable sleeve 4.

E—E denote the lower end cross or transverse bars which have their extremities resting upon the end portions of the bars A as is particularly illustrated in Fig. 1 of the accompanying drawings, and F—F denote the

upper transverse or cross bars which rest upon the end portions of the upper bars B. The overlying portions of the bars A and E and the bars B and F are provided with co-
5 incising or registering openings through which are directed the reduced extensions or integral pins 5 extending longitudinally from the opposite ends of the corner uprights or bars C. The opposite ends of the intermediate uprights or bars D are also provided at their opposite ends with the longitudinally disposed reduced extensions or integral pins 6 adapted to be directed through suitable openings in the bars A
10 and B.

Straddling the overlying portions of the bars A and E are the substantially U-shaped clips 7 and through the end portion of which the lower extensions or pins 5 of the corner uprights or bars C are also directed. The upper portion of each of the clips 7 is provided with or extended to form an up-
20 standing hook member 8 preferably contacting with the adjacent corner upright or bar C and with which is engaged an annular member or ring 9 through which the bar C is also directed.

The bars A adjacent the intermediate uprights or bars D are also straddled by the additional clips 10 provided with the up-
30 standing hooks 11 preferably contacting with the inner faces of the uprights or bars D and through the returned portions of which are threaded the screws 12 for a purpose to be hereinafter more particularly referred to.

The upper longitudinal bars B are also straddled by the clips 14 provided with the depending hook member 15 also contacting with the inner faces of the intermediate uprights or bars D and having threaded through their returned portions the clamping screws 16 as will also be hereinafter referred to. The lower portions of the clips 10 and the upper portions of the clips 14 have extended therethrough the extensions or pins 6 of the intermediate uprights or bars D, whereby it will be at once self-evident that said clips 10 and 14 are afforded a fixed position upon the bars A and B. Engaged with the upper extensions or pins 5 of the uprights or bars C are the annular members or rings 17 for a purpose to be explained.

M denotes a continuous flexible member and as herein embodied said member M has a portion a extending transversely of my improved structure and is threaded through the forward rings 17 at the entrance end thereof and extends downwardly adjacent each of the uprights or bars C at the entrance end, as indicated at b, and is threaded through the coacting rings 9. The member M extends upwardly, as at c, and passes over
65 the hook members 10 and then extends down-

wardly, as at d, and is threaded through the annular members or rings 9 coacting with the uprights or bars C at the closed end of the tent. The member M then extends upwardly, as at e, and is threaded through the rings 17 and transversely adjacent the upper rear bar F, as indicated at f. The portions e of the flexible member M are threaded through the annular member or ring 18 whereby the same effectively intersect the closed end of my improved structure.

Underlying each of the hook members 11 is a flexible member M' which has its opposite-end portions engaged, as at 19, with the portions c and d of the member M, said connections 19 being such as to permit the portions c and d of the member M to have sliding movement independently of the connections 19.

T denotes a tensioning member which comprises two relatively adjustable members 20 capable of relative longitudinal movement upon axial rotation of one or both of said members and which, as herein disclosed, is afforded through the medium of the threaded connection 21 between said members 20.

In swiveled connection with the outer ends of each of the sections 20 of the tensioning member T are the hook members 22 engageable with the portions a and f of the flexible member M, whereby it will be at once self-evident that upon inward movement being imparted to the sections 20 requisite strain will be imposed upon the member M and the members M' to maintain the various bars of the frame in assembled relation. It is also thought to be clearly obvious that upon causing the sections to move outwardly sufficient slack may be attained by the member M and the members M' as to permit the tent frame to be knocked down or collapsed.

The clamping screws 12 and 16 as herein-before referred to serve to prevent the member M and members M' from becoming displaced from their coacting hook members 11 and 15 and if preferred said clamping screws 12 and 16 may be caused to directly engage with the adjacent flexible members so that said members are fixedly connected thereto. It is also to be observed that the hook members 22 have threaded through the returned portions thereof the clamping screws 28 for a similar purpose.

As illustrated in Fig. 2, W denotes the walls of my tent which may be of any suitable material and in order to effectively maintain said walls W in applied position upon the frame, it is to be noted that the longitudinal marginal portions of the top wall are provided with the upstanding and downwardly opening sockets 24 and in which are adapted to be seated the upper extensions 5 and 6 of the uprights or bars C and D, respectively.

In Fig. 1 the bars A and B are shown

provided with additional openings 25. These are to permit the use of additional intermediate uprights or bars if the requirements of practice should so necessitate, and 5 the upper bar F at the entrance end of the tent is shown with the additional openings 26 for a similar purpose, it being understood that the additional uprights or bars which may be employed in connection with the 10 entrance end of a tent are to extend down about only one-third of the height of the frame so that no obstruction will be offered in entering the tent.

Detachably engaged with each of the 15 upper transverse or cross bars F are the posts 27 with which is detachably engaged the opposite extremity of the bar G which is adapted to underlie the top wall W of the tent to produce a water shed, as is believed to be clearly shown in Fig. 2. It 20 is also preferred that this bar G be comprised of detachable sections connected one to the other by a removable sleeve 28 as has been set forth relative to the bars A and B.

25 It has also been found of advantage, as illustrated in Fig. 5, to provide the end portions of the bars and preferably the horizontal bars with the marginal and end reinforcement 29 preferably of metal, as it is 30 to be understood that for all ordinary usages it is my intention to make the several bars of wood, although I do not wish to be understood as limiting myself in this respect.

As disclosed in Fig. 7 of the accompanying 35 drawings, I show my improved tent as being used as a garage and when so employed the tent is adapted to be disposed over the vehicle as indicated by V in said Fig. 7, and in order to so position the vehicle 40 it is preferred that the tent or structure be up-ended. This may be accomplished in any manner desired but as herein embodied I employ a conventional crane 30 with which 45 coacts the flexible member 31 suitably secured to an end portion of the structure.

To prevent unauthorized use of the vehicle I employ the elongated member 32 adapted to be disposed beneath the vehicle after the same has been properly positioned 50 within the tent structure and of such a length as to have its opposite end portions underlie the lower cross or transverse bars E. At a predetermined point inwardly of 55 each end the elongated member 32 has hingedly connected therewith, as at 33, the upstanding member 34.

Adjacent its outer or upper end the member 34 is provided with the outwardly and laterally directed arm 35 arranged to underlie 60 an upper cross or transverse bar F, and above or in advance of the arm 35 the member 34 has hingedly connected therewith, as at 36, a second arm 37 adapted to overlie the top of an upper cross or transverse bar 65 F. The extremities of the arms 35 and 37

are preferably provided with the openings 38 with which suitable locking means is adapted to be engaged.

As illustrated in Figs. 9 and 10, I disclose a tent of substantially a cylindrical or conical type and wherein the top and bottom bars A' and B', respectively, are disposed in predetermined angular relation and have their adjacent ends overlapping, and coacting with the overlapping portions of the 75 lower bars A' are the hook members 8' of a character substantially the same as has been set forth relative to the hook members 8. C' denotes uprights or vertical bars coacting with the overlapping portions of the bars 80 A' and B' as has been set forth relative to the uprights or vertical bars C.

Loosely engaged with the upper extensions or pins 5' of the uprights or vertical bars C' are the annular members or 85 rings 17'.

As herein embodied, the frame afforded by the bars A', B' and C' is substantially octagonal in plan and at substantially the 90 axial center of said frame is arranged the tensioning device T'.

As herein disclosed, the tensioning device T' comprises a lower plate 39 which, as disclosed in Fig. 10 of the accompanying drawings, may rest directly upon a supporting surface, although this is not at all times essential. It is preferred however that the plate 39 contact directly with the supporting 95 surface so that the tensioning device T' may also serve as a center pole so that the top of 100 the tent may be caused to form an effective water shed.

40 denotes a substantially horizontally disposed annular member maintained in predetermined vertical spaced relation relative 105 to the plate 39 through the medium of the interposed rods 41 suitably secured to said plate 39 and the annular member 40.

42 denotes a vertically disposed member swiveled, as at 43, to the plate 39. Adjustably connected with the upper end of said member 42 for endwise movement is the rod 44 having engaged with its upper portion the disk or plate 45 provided adjacent its periphery with the openings 46 through 115 which is threaded the flexible member M'.

It is preferred that the flexible member M' be continuous and as herein disclosed a portion of said member as indicated at z is engaged with the hook members 8 of adjacent uprights or vertical bars C' and extends upwardly, as at y, through the rings 117' in substantially vertical alinement with the hook members 8 and thence inwardly, as at x, and over the annular member or ring 40 120 and the plate or disk 45. By this arrangement it will be perceived that alternate faces of the frame are provided with the portions z of the flexible member M'. It is preferred 125 that the portions y of the intermediate faces 130

be disposed through the restricted annular members, or rings 47 as particularly illustrated in Fig. 10 for purposes which are believed to be clearly apparent to those skilled in the art to which my invention appertains.

By imparting requisite rotation to either the member 42 or the rod 44 it will be perceived that sufficient strain may be imparted to the flexible member M² to assure the various bars A', B' and C' being maintained in assembled relation and that by imparting a reverse rotation to either the member 42 or the rod 44, the frame of my improved tent as embodied in Figs. 9 and 10 may be readily and conveniently collapsed.

It is also to be understood that if desired suitable hooks or the like may be secured to the outer margins of the bars A, B, E and F so that a mosquito bar may be disposed around the frame when it is preferred to employ my improved device as a sleeping tent.

From the foregoing description, it is thought to be obvious that a tent constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. In combination with a supporting structure for a tent or the like comprising vertically spaced end bars, a locking means including an elongated member having its opposite extremities underlying the lower end bars of the structure, and members carried by the elongated member and provided with means for securing the same to the upper end bars of the structure.
2. A supporting structure for a tent or the like comprising a plurality of substantially horizontally disposed upper and lower bars, the adjacent extremities of the bars being in overlying relation, vertically disposed bars for maintaining the lower bars and upper bars in predetermined spaced relation, said vertically disposed bars having their extremities disposed through the overlying portions of the bars, and a single tensioning device coacting with all of the extensions of the vertical bars for maintaining the structure in assembled relation.
3. A supporting structure for a tent or

the like comprising a plurality of substantially horizontally disposed upper and lower bars, the adjacent extremities of the bars being in overlying relation, vertically disposed bars for maintaining the lower bars and upper bars in predetermined spaced relation, said vertically disposed bars having their extremities disposed through the overlying portions of the bars, a flexible member operatively engaged with all of the extensions of the vertical bars, and a tensioning device coacting with said flexible member.

4. A supporting structure for a tent or the like comprising a plurality of substantially horizontally disposed upper and lower bars, the adjacent extremities of the bars being in overlying relation, vertically disposed bars for maintaining the lower bars and upper bars in predetermined spaced relation, said vertically disposed bars having their extremities disposed through the overlying portions of the bars, members detachably engaged with the extensions of the vertical bars, a flexible member operatively engaged with and common to all of said last named members, and a tensioning device coacting with the flexible member.

5. A supporting structure for a tent or the like comprising a plurality of substantially horizontally disposed upper and lower bars, the adjacent extremities of the bars being in overlying relation, vertically disposed bars for maintaining the lower bars and upper bars in predetermined spaced relation, said vertically disposed bars having their extremities disposed through the overlying portions of the bars, members detachably engaged with the extensions of the vertical bars, a flexible member operatively engaged with the detachable members, and a tensioning device coacting with the flexible member, certain of said detachable members being hooks and the remainder of said members comprising rings.

6. In combination with a supporting structure for a tent or the like comprising vertically spaced bars at each end thereof, a locking means including an elongated member having its opposite extremities underlying the lower bars at the ends of the structure, members pivotally engaged with the elongated member, and securing means carried by said pivoted members and adapted to coact with the upper end bars of the structure.

In testimony whereof I hereunto affix my signature in the presence of two witnesses.

JOHN H. BREWER

WITNESSES:

M. J. BREWER,
W. H. FINLEY
